UNITED STATES PATENT OFFICE

169,016

DRESS

Karl E. Sedlacek, Los Angeles, Calif.

Application August 30, 1952, Serial No. 21,243

Term of patent 3½ years

(Cl. D3—26)

To all whom it may concern:

Be it known that I, Karl E. Sedlacek, a citizen of the United States, residing in Los Angeles, in the county of Los Angeles and State of California, have invented a new, original, and ornamental Design for a Dress, of which the following is a specification, reference being had to the accompanying drawing, forming part thereof.

Fig. 1 is a front elevational view of a dress, showing my new design.

Fig. 2 is a side elevational view thereof.

The ornamentation on the back of the dress is the same as that shown for the front.

I claim:

The ornamental design for a dress, substantially as shown and described.

KARL E. SEDLACEK.
